SAFETY RAZOR

Samuel C. Stampleman, Cohasset, and Nicholas Testi, Boston, Mass., assignors to Gillette Safety Razor Company, Boston, Mass., a corporation of Delaware

Application April 8, 1944, Serial No. 530,160
In Canada October 16, 1943

7 Claims.

(Cl. 30—72)

This invention relates to safety razors of the type in which a thin flexible blade is supported in a condition of transverse curvature between cooperating blade-clamping members. In such razors, it is the practice to adjust blade exposure by varying the pressure of engagement of the blade-clamping members upon the blade; for example, by releasing the pressure and allowing the blade to flatten slightly the degree of its edge exposure is increased. Heretofore difficulty has been encountered because a relatively slight amount of release in the clamping pressure on the blade has resulted in an abrupt increase of edge exposure and, furthermore, relaxing the pressure has introduced a looseness into the connection between the head and the handle which may permit the head to twist with danger to the user.

The object of the present invention is to provide a fine, easily controlled adjustment of blade exposure, to retain a reliable connection between the head and the handle throughout on full range of adjustment and to eliminate or dampen chattering or vibration of the blade which is encountered in shaving with the blade loosely clamped. All of these advantages are achieved in a compact construction in accordance with our invention, as well as convenience of operation and capacity for a vernier type of adjustment.

With these objects in view an important feature of our invention consists in a spring housed in a chamber of variable effective length and acting at all times to urge the blade-clamping members into clamping engagement, in combination with means for positively and accurately varying the effective length of the spring chamber, thereby adjusting the spring and regulating the pressure of the clamping members on an interposed blade with a high degree of precision.

These and other features of the invention will be best understood and appreciated from the following description of a preferred embodiment thereof selected for purposes of illustration and shown in the accompanying drawing, in which:

Fig. 1 is a view of the razor in longitudinal section showing a blade clamped in shaving position;

Fig. 2 is a similar view, partly in elevation and partly in longitudinal section, showing the blade as slightly released for increased blade exposure;

Fig. 3 is a similar view showing the blade completely released;

Fig. 4 is a fragmentary view in elevation of a portion of the razor handle; and

Fig. 5 is a plan view of a blade upon the guard.

- 5 The illustrated razor comprises a cap 10 rectangular in outline and provided with a transversely concave blade-engaging face. The cap is rigidly secured to the upper end of a stem or spindle 11 which is provided with a flattened section 12 adjacent to the cap and has its lower end portion 13 reduced in diameter at an intermediate shoulder in the stem. The guard or blade-supporting member 14 is similar in shape to the cap but somewhat wider, being provided 10 with marginal guard bars which extend downwardly and outwardly beyond the edge of the blade. The guard 14 is preferably formed integral with a head 15 which is bored to receive the stem 11 and provided externally with a shoulder. A cylindrical barrel 16, fitting over the lower end of the head 15 and engaging with its shoulders, telescopically encloses the stem 11. In the lower end of the barrel 16 is provided an elongated cylindrical nut 17 having a bevelled 20 circumferential shoulder 18 on which may be inscribed a scale, and a reduced elongated shank 19, the latter being internally threaded and provided with an external circumferential groove in which is received an internal rib 20 formed 25 in the barrel 16. The rib and groove form a positive rotary connection between the barrel 16 and the nut 17 permitting the nut to turn freely but holding it securely against longitudinal movement with respect to the barrel.
- 30 A hollow sleeve 21 surrounds the reduced lower end portion 13 of the spindle within the barrel 16 and provides an elongated chamber for a compression spring 22 which surrounds the reduced portion 13 of the stem. Above and beyond the spring chamber the sleeve 21 is provided with a straight slot 23 into which projects a short pin 24 from the portion 13 of the stem, thus providing a sliding non-rotating connection between the sleeve and the stem. At its 35 lower end the stem is provided with a nut 25 or abutment against which bears the spring. The distance between the inner face of the nut and the shoulder of the stem 11 is greater than the length of the sleeve 21 by substantially the pitch of the thread of the sleeve. The sleeve is movable in a path determined by these two limits and its movement is effected positively by turning the cylindrical nut 17 with which the sleeve has threaded connection. When the sleeve is 40 moved upwardly the effective length of the
- 45
- 50
- 55

spring chamber is increased and the compression of the spring thus reduced. When the sleeve 21 is moved down its upper or inner end forces down the upper end of the spring and so increases its compression.

The razor herein illustrated is designed to employ a thin flexible blade 30 recessed in each corner to provide elongated unsharpened end portions and having a longitudinal slot which opens out through one end of the blade. It will be understood, of course, that the invention may be embodied in other types of razor designed to handle other types of blade. The blade herein shown is merely representative of one of many blades that may be employed with equal advantage although requiring appropriate variations in detail of razor construction. However, when an open-ended blade is used like that herein shown the guard may be provided with a longitudinal blade-locating rib 26 and an overhanging retaining flange 27. This permits the blade to be presented to the guard and removed therefrom by longitudinal movement, the blade being preliminarily retained in place by the retaining flange 27. The flange is received within the concavity of the cap without at all interfering with the clamping engagement of the blade by the latter.

In Fig. 1 the nut 17 is represented as being rotated to the limit of its blade-clamping movement, that is to say it has been rotated clockwise drawing the sleeve 21 downwardly into contact with the nut 25 on the end of the stem, compressing the spring 22 to the limit and, by its positive engagement with the nut 25, depressing the stem and the cap until the cap is brought into solid clamping engagement with the blade 30. The blade is thus positively clamped in condition of maximum transverse curvature and minimum edge exposure. In this condition it will be noted that the upper end of the sleeve has been removed appreciably below the shoulder in the stem.

Assuming now that the user wishes to increase the edge exposure of the blade: With this end in view he may retract the nut 17 any desired number of divisions indicated by the scale of the bevelled portion 18 thereof. Fig. 2 shows the parts of the razor in the position they would occupy with the nut 17 retracted one full turn. Under these circumstances the sleeve 21 is positively moved upwardly from the position shown in Fig. 1 to a position in which it just touches the shoulder of the stem 11. In this movement of the sleeve the effective length of the spring chamber is increased and the compression of the spring relaxed. The stem 11 moves very slightly because the spring 22 is still under substantial compression and this tends to hold the nut 25 and the stem downwardly. It is only as the compression of the spring 22 becomes weaker than the spring of the blade 30 that the stem 11 and the cap 10 are permitted to make any separating movement with respect to the guard. When such separation occurs and the blade flattens, its edge exposure increases although yielding pressure is maintained because there is always some compression in the spring 22 and it is this residual compression that prevents the head from swinging loose while the razor is in use and also dampens or eliminates chattering of the blade.

When it is desired to remove the blade for replacement or cleaning, the nut 17 may be retracted to the limit of its movement, that is to say, until the nut 25 bottoms in the recess of the cylindrical nut 17 as suggested in Fig. 3. It

will be understood that the sleeve 21 is first moved on the stem 13 to increase the effective length of the spring chamber to a maximum and then, when the sleeve encounters the shoulder in the stem, the latter is positively lifted to some such position as is shown in Fig. 3. When the cap and guard are disposed in this separated relation the blade may be freely presented to or removed from its position upon the guard.

It is a characteristic of the construction above discussed that the cylindrical nut 17 is effective first to shift the sleeve 21 longitudinally upon the stem, and then, when the sleeve has engaged the shoulder of the stem, to shift the sleeve and the stem bodily in positively separating the cap and guard.

Having thus disclosed our invention and described in detail one illustrative embodiment thereof, we claim as new and desire to secure by Letters Patent:

1. A safety razor comprising a guard having a convex blade-flexing face, a cap having a co-operating concave blade-flexing face, a stem carrying the cap, a handle connected to the guard, and connections between the stem and guard including a threaded sleeve movable on the stem, a spring enclosed within the sleeve and acting at all times on the stem to move the cap and guard together, and a threaded nut associated with the handle and having also threaded connection with the sleeve for positively moving the sleeve on said stem to vary the adjustment of said spring.

2. A safety razor comprising cooperating blade-clamping members having telescopically arranged stem and barrel connected thereto respectively, a sleeve forming an open-ended chamber about the stem, a compression spring in said chamber, a nut on the stem closing the outer end of said sleeve and supplying an abutment for said spring, and means for longitudinally adjusting the sleeve on said stem.

3. A safety razor comprising cooperating blade-clamping members, one having a barrel and the other a stem concentrically arranged therein and provided with a shoulder and an end abutment, a sleeve shorter than the distance between said shoulder and abutment, a spring in the sleeve bearing against the abutment at one end and reacting at its other end against the stem, and means associated with the barrel for adjusting the position of the sleeve and thereby regulating the compression of the spring.

4. A safety razor including in its structure cooperating blade-clamping members having telescopic handle sections, a sleeve movably mounted on one handle section and having an elongated spring chamber therein, a spring in said chamber connected at opposite ends to the blade-clamping members and tending at all times to hold them together, and means mounted on the other handle section for increasing the effective length of the spring chamber and so reducing the pressure of the blade-clamping members.

5. A safety razor including in its structure cooperating blade-clamping members, one having a solid shouldered stem with an end abutment and the other an enclosing barrel, an externally threaded sleeve movable upon the stem between its shoulder and said abutment and providing an elongated spring chamber, a spring therein, and a nut rotatable outside the barrel and held against longitudinal movement with

respect thereto, said nut having a threaded connection with said sleeve.

6. A safety razor including in its structure cooperating rigid blade-clamping members, one having a stem with an intermediate shoulder and an end abutment and the other a barrel enclosing the stem with clearance, a sleeve having a non-rotatable connection with the stem and being movable longitudinally thereon between said shoulder and end abutment, a compression spring housed within said sleeve and acting through said end abutment to maintain said blade-clamping members under pressure, and a graduated adjusting device rotatable outside said barrel and held against longitudinal movement with respect thereto, said device hav-

ing a threaded connection with said sleeve whereby the sleeve may be moved relatively to the stem or bodily with the stem.

7. A safety razor including in its organization 5 a cap and a guard shaped to clamp a flexible blade between them, a hollow handle connected to one member, an elongated chamber enclosed within the handle, a spring held under compression in said chamber and having connections with both the cap and guard tending always to move them together, and means for varying the effective length of said chamber while maintaining always the spring clamping pressure of the cap and guard.
